UNITED STATES PATENT OFFICE.

ELMER E. HARPER, OF KANSAS CITY, MISSOURI.

DRY-MATERIAL-FEEDING MACHINE.

Application filed February 1, 1924. Serial No. 689,977.

To all whom it may concern:

Be it known that I, ELMER E. HARPER, a citizen of the United States, residing at Kansas City, in the county of Jackson and State of Missouri, have invented certain new and useful Improvements in Dry-Material-Feeding Machines; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a dry-material feeding machine. It is intended for delivering measured quantities of dry material and it is particularly applicable as a machine for delivering measured quantities of dry material to a liquid containing tank or receptacle.

The illustrated embodiment of the invention is designed for delivering measured quantities of dry materials to a dissolving tank. Any suitable dry material may be fed through the machine so I do not wish to be limited to the exclusion of any particular material but by way of example, lime or lime and alum may be used.

The invention comprehends the inclusion of a hopper having a discharge orifice through which measured quantities of the dry material may be fed on to a receiving table to be mechanically moved off into the tank or receptacle by a sweep operated by means for varying the amplitude of movement of the sweep so that varying quantities of the material may be swept off the table by intermittent motions communicated to the sweep by the operating mechanism of the machine. Means is provided for constantly agitating the material in the hopper so that the hopper will not become clogged and if desired an automatic control may be embodied in the machine for controlling the movement of the sweep so as to vary the quantity of dry material fed into the receptacle in proportion to the amount of water to be treated.

The specific construction of the illustrated embodiment of the invention will be described hereinafter, reference being had to the accompanying drawings, in which:

Fig. 1 is a perspective view of a dry-material feeding machine constructed in ac-

cordance with my invention, parts being broken away to better illustrate certain other parts.

Fig. 2 is a cross sectional view through the hopper showing the agitators in elevation, the table being also shown in section.

Fig. 3 is a longitudinal sectional view through the hopper.

Fig. 4 is a detailed view of an automatic feed control attachment, and

Fig. 5 is a plan view of the liquid receptacle.

The hopper 1 is illustrated as supported upon suitable legs or standards 2. The hopper has a constricted bottom provided with an outlet opening 3 through which the material may be fed onto a receiving table to be hereinafter referred to. Depending from the hopper is a skirt 5 through which project valve supporting rods 6 and 7 which carry a valve 8 in the form of a slide, the rods being movable longitudinally in the skirt to move the valve across the opening 3 to vary the effective port area thereof. Mounted in suitable bearings 9 and 10 is a rock shaft 11 which extends through the hopper and which carries spaced segmental agitators 12 so that when the rock shaft is rocked the agitators will agitate the material within the hopper so as to prevent it from caking. Between the two sets of segmental agitators illustrated is a depending agitating arm 13 having an L-shaped extension 14 movable in an arc substantially parallel to the bottom of the hopper so that it not only constitutes an agitator but also a scraper to prevent accumulation of the dry material on the bottom of the hopper. The rock shaft 11 is actuated by a crank arm 15, receiving its motion from a link 15', eccentrically connected to the disk 16 on a reduction gear 17 receiving its motion from a motor 18 through a belt 19 and pulley 20, the latter being part of the reduction gear.

Any suitable reduction gear may be employed, but I recommend a worm gear of appropriate construction and for convenience an electric motor may be employed. The crank arm 14 carries a depending end 21 to which one end of a sweep arm 22 is loosely connected. The sweep arm is located between two lugs 23 and 24 carried by the end 21 and in the lugs are adjustable stop screws 25 and 26, which may be adjusted in the lugs to vary the distance between their ends and since the sweep arm

105

110

is loosely connected to the depending segmental end 21 of the crank 14, it will be apparent that there is a lost motion connection between the crank arm 14 and the sweep arm 22, hence the amplitude of movement of the sweep arm will be varied by adjusting the set screws 25 and 26. The sweep arm 22 carries a clamping bar 27 so that a sweep 28 may be clamped to the arm 22 as 10 will be clearly seen by reference to Fig. 1.

The sweep moves over a receiving table 29 supported by the rod 30 adjustable in the vertical slots 31 and 32 of the skirt 5 so that the table may be adjusted vertically 15 with respect to the bottom of the hopper, it being obvious that the amount of material deposited upon the table through opening 3 will vary according to the relative distance between the table 29 and the bottom of the 20 hopper.

When the motor is operated the gearing will cause a rocking motion to be imparted to the arm 15 to rock the shaft 11. Since the agitators and the scraper are all rigid 25 with the shaft 11, it is obvious that the material will be agitated in the hopper so it will be in a loose, finely divided condition to feed by gravity through the opening 3, the amount of material fed onto the table 30 29 depending of course upon the effective port area of the opening 3 and the position of the table 29 with respect to the bottom of the hopper. The amplitude of movement of the sweep will depend upon the position 35 of the set screws 25 and 26 for if the set screws 25 and 26 are far apart, it follows there can be an appreciable movement of the depending end 21 before any movement is communicated to the sweep arm 22, but 40 if the set screws are close together, there will be a greater movement imparted to the sweep arm and consequently a greater amount of material will be swept off the table than would be possible with a slight 45 movement of the sweep. The material falling into the tank 4 will be agitated so as to thoroughly co-mingle with the water therein and be equally dissolved. This effect can be accomplished by introducing the water 50 through the pipes 33 and 34 which enter the tank 4 at a tangent so as to cause the water to swirl about the axis of the tank, the discharge from the tank being through a pipe 35 communicating with chamber 35' 55 separated from the main portion of the tank by a partition 36 which extends from the top nearly to the bottom of the tank so that the chamber 35' will be in the middle of a quiescence zone separated from the agitating chamber 37.

It will be apparent that a device constructed in accordance with my invention will feed measured quantities of dry material into a liquid receptacle or tank in uniform doses, the size of the dose varying 60

according to the adjustments made and if desired, I may provide an attachment for varying the dose in proportion to the amount of water to be treated. The tank 38 may be connected by suitable piping to 70 the water supply to be treated, so that the float 39 will rise or fall in proportion to the flow of water to be treated. In the tank is a float 39 connected to a lever arm 40 by a connection 41, the lever arm being 75 adapted to rock about its pivot 42 upon a rise and fall of the float 39. The lever arm carries a geared segment 43 which meshes with a geared segment 44 pivoted at 45. The segments carry cams 46 and 47 which are 80 adapted to be brought close together when the float drops and to spread apart when the float rises. These cams may act as stops for a pin 48 extending through the lower end of the sweep arm 32. The adjusting 85 screws 25 and 26 will be set to give the maximum stroke to the spring sweep arm 22 and the sweep is set to deliver the required amount of chemical when the float 39 is at its greatest height and the cams 90 are farthest apart. If the water level is lowered, the float 39 will drop, bringing the cams 46 and 47 closer together, thus reducing the arc through which the sweep 95 may travel. This may continue until the travel of the sweep is entirely stopped by the cams. When the float rises the opposite action will take place.

I have specifically described the preferred embodiment of my invention, but I do not 100 wish to be limited to the exact details of construction shown, but reserve the right to make such changes in form, proportion and minor details of construction as properly come within the scope of the appended 105 claims.

What I claim and desire to secure by Letters-Patent is:

1. In a machine for feeding dry material, a hopper having a discharge opening in its 110 bottom, a table below the hopper to receive material from the hopper, a horizontal shaft in the hopper, a vibratory agitator carried by the shaft and a rocking sweep carried by the shaft, said sweep including a downwardly projecting arm having a right angularly projecting blade movable over the face of the table.

2. In a machine for feeding dry material, a hopper having a discharge opening in its 115 bottom, a valve for effecting the port area of the opening, a table below the hopper in line with the opening to receive material from the hopper, a rock shaft in the hopper, an agitator in the hopper carried by the rock shaft and a vibrating sweep arm connected to the shaft and movable over the table for moving the material off the table.

3. In a machine for feeding dry material, a hopper having a discharge opening in its

bottom, a valve for varying the effective port area of the opening, a table below the hopper to receive material discharged through the opening, agitators in the hopper, a rock shaft for operating the agitators, a crank arm on the rock shaft, means carried by the rock shaft for supporting a sweep arm, a sweep arm having a lost motion connection with said supporting means whereby the supporting means may have certain initial movement before actuating the sweep arm and a sweep carried by the arm for discharging the material off the table.

4. In a machine for feeding dry material, a hopper having a discharge opening, a rock shaft transversely of the hopper, agitators connected to the rock shaft, one of which has a portion movable in an arc past the opening, a rock shaft operating crank arm fast to the rock shaft, means for swinging the crank arm back and forth to rock the shaft, a segment carried by the shaft, a sweep arm pivoted to the segment, adjustable stops on the segment on opposite sides of the sweep arm, a table below the hopper in line with the opening and a sweep carried by the sweep arm.

5. In a machine for feeding dry material,

a hopper having a discharge opening, a rock shaft transversely of the hopper, agitators connected to the rock shaft, one of which has a portion movable in an arc past the opening, a rock shaft operating crank arm fast to the rock shaft, means for swinging the crank arm back and forth to rock the shaft, a segment carried by the shaft, a sweep arm pivoted to the segment, adjustable stops on the segment on opposite sides of the sweep arm, a table below the hopper in line with the opening and a sweep carried by the sweep arm, and a valve for varying the effective port area of the opening.

6. In a machine for feeding dry material, a hopper having a discharge opening in its bottom, a table below the opening onto which the material may be fed, a sweep for discharging the material off the table, a sweep arm to which the sweep is connected, an operating means for the sweep arm and float actuated means for controlling the amplitude of movement of the sweep arm, said float actuated means including cams movable toward and away from the sweep arm.

In testimony whereof I affix my signature.

ELMER E. HARPER.
